UNITED STATES PATENT OFFICE.

HENRY SIMON, OF SANTA ANA, CALIFORNIA.

MAGAZINE SCREW DRIVER.

Application filed November 28, 1922. Serial No. 603,825.

To all whom it may concern:

Be it known that I, HENRY SIMON, a citizen of the United States, residing at Santa Ana, in the county of Orange and State of California, have invented new and useful Improvements in Magazine Screw Drivers, of which the following is a specification.

This invention has reference to multiple tools, and more particularly to a magazine screw driver adapted to contain a plurality of blades which may be selectively projected and locked in position for use by a simple manipulation of the magazine body, without removing the blades therefrom.

In the ordinary magazine screw driver, several blades are carried loosely in the hollow handle, and in order to change the blades, it is necessary to remove the cap which closes the end of the handle, take out the blade, insert it in the chuck, close the chuck, and fasten the cap again in place.

In my former application, Serial No. 530,588, filed January 20, 1922, there is disclosed a magazine screw driver which is so constructed that by turning the tool in different directions, different blades may be made to move into working position where they are securely locked by a chuck and may be easily retracted into the magazine body.

The general object of the present invention is to simplify and otherwise improve the construction shown in my aforesaid application, whereby the cost of manufacture is reduced, a number of unnecessary parts are eliminated, and other desirable new features are added which facilitate the manipulation and operation of the tool, one of such features being a spring to automatically retract the tool with the hollow handle.

In my former construction, the screw driver blades were contained within a so-called change shell which was attached to and movable with the chuck. In the present construction, the change shell, in the sense in which the term is used in reference to my former construction, has been eliminated altogether, the body of the handle itself serving for the purpose of selecting the blade to be used, with the result that the weight of the tool and the size of the body are reduced and the construction thereof simplified.

The chucking and retracting action is also rendered more rapid and convenient, the blade in use can be set more rigidly, and in addition, the blades not in use can be in-

stantly stopped from rattling by a simple turn of the end cap, this feature not entailing any extra parts.

There are other features of construction which represent improvements over the prior construction, but they will appear as the description is proceeded with.

The invention will be best understood from a consideration of the following detailed description, taken in connection with the accompanying drawings forming a part of this specification, with the understanding, however, that the invention is not confined to any strict conformity with the showing of the drawings, but may be changed and modified so long as such changes and modifications mark no material departure from the salient features of the invention as expressed in the appended claims.

In the drawings:

Fig. 1 is a side elevation of a screw driver embodying the invention and showing one of the blades projecting and clamped.

Fig. 2 is a longitudinal central section with some parts in elevation, the position being the same as in Fig. 1.

Fig. 3 is a longitudinal central section at right angles to the plane of Fig. 2.

Fig. 4 is a plan view of one of the screw driver blades.

Fig. 5 is an elevation of the chuck body with the chuck cap removed.

Fig. 6 is a front end view of the tool with a blade clamped in working position.

Fig. 7 is a front end view of the tool in position for projecting one of the blades.

Fig. 8 is a cross section on the line 8—8 of Fig. 1, showing the means for limiting the rotation of the chuck cap on the chuck body.

Figs. 9 and 9^a are cross sections on the line 9—9, Fig. 1, showing the blades adjusted in two different positions.

Fig. 10 is a cross section on the line 10—10 of Fig. 1, showing the end cap turned to bind the blades.

Fig. 11 is a side elevation of the inner selective sleeve.

Fig. 12 is a front end elevation of the sleeve.

Fig. 13 is a side elevation of the end cap detached.

Fig. 14 is a perspective view of a pressed steel plug which is used within the end cap.

Referring more particularly to the drawings, the tool comprises a main barrel or

magazine 4 of substantially cylindrical form, and adapted to contain a plurality of screw driver blades 1, 2 and 3, formed preferably of stamped metal of appropriate shape and rigidity and of even thickness throughout, except at the point which is tapered, and of different sizes.

The magazine 4 is provided with a forward extension or chuck body 5 which may be integral with the magazine, or suitably secured thereto by a close fitting frictional engagement and by a screw 6 or the like. The chuck body 5 has a reduced portion 7, the internal diameter of which is of sufficient extent to closely fit the base portion of the shank of one of the screw driver blades. The chuck body has at its forward end a still further reduced portion 8, which is solid except for a slot 9, that extends therethrough, as best seen in Fig. 5, and is located in the longitudinal center of the tool.

Surrounding the reduced portions 7 and 8, of the chuck body, is a chuck cap 12, having its forward end contracted and inwardly bent as at 11, to closely surround the outer end of the reduced portion 8. The diameter of the portion 8, at the extremity of the chuck body, is substantially equal to the width of the screw driver blade between the notches 10. The contracted portion 11 of the chuck cap is provided with opposed notches 15 (Fig. 6), which, are each slightly wider than the slot 9, and when brought into alignment with the slot 9 in the end of the chuck body, as shown in Fig. 7, form a continuous passage wide enough to permit the projection of one of the screw driver blades. When the chuck cap 12 is partially rotated to bring the notches 15 out of alignment with the slot 9, as shown in Fig. 6, the contracted end 11 of the chuck cap will ride in the notches 10 of the blade and lock the same in projected position.

In order to secure the chuck cap to the chuck body so that it may rotate to a limited extent thereon, the cap is provided with a slot 13, through which a screw 14 is secured in the reduced end portion 8 of the chuck body. Preferably, a spring washer 16 is inserted between the chuck cap and reduced portion 8 to provide the required degree of friction therebetween, and said washer is held in position by the screw 14. (Figs. 1, 3 and 8).

A sleeve 17 is provided within the chuck body 5, and held for sliding longitudinal movement by means of a slot 18, which is guided on the screw 6, the forward end of the sleeve 17 being provided with an opening 19, which is of a special configuration for determining the selection of the blade to be projected, as hereinafter explained. The sleeve 17 is normally urged inwardly by a compression spring 20, which acts be-

tween the front end of the sleeve and the shoulder formed by the reduced portion 7 of the chuck body. The screw 6 not only holds the magazine and chuck body from rotation, but holds the sleeve 17 from turning and prevents it being forced down into the magazine too far.

The blade is widened at the butt end and provided with ears 21, which, when the blade is projected, engage the flange 19^a, formed by the opening 19 of the sleeve, and when the blade is fully projected, with the contracted portion 11 of the chuck cap engaged in the notches 10, the sleeve 17 will be advanced by the ears 21 of the blade 80 acting against the flange 19, thus placing the spring 20 under compression, so that, when the blade is released by a rotation of the chuck cap to bring the notches 15 into alignment with the notch 9, if the tool is held with the handle extending downwardly, the pressure of the spring 20, when suddenly released, will cause the blade to snap inwardly into the casing. This is one of the novel features of this invention. 90

The rear end of the magazine 4 is closed by an end cap 22, provided with a reduced forward portion 23, having a T-shaped slot 24, within which extends a pin 25, that is secured in the rear portion of the magazine 95 or barrel 4. The longitudinal portion of the slot 24 permits the ready insertion of the end cap into position, and it is locked in this position, as well as restricted in its rotary movement, by a partial rotation in 100 either direction.

The free end portions 26 of the reduced end 23 are slightly bent outwardly, making them resilient, so as to press against the inner surface of the barrel 4, and thus cause sufficient friction to retain the end cap in any position to which it may be adjusted.

The base portions or butts of the blades are held in position by a pressed steel plug 27 (Fig. 14), which has a pair of opposed prongs 28 and 30, the former having a pointed laterally projecting tip or spur 28^a, which is adapted to be received in one of the holes 29 in the end cap 22 to hold the plug therein from either longitudinal or rotative movement. Between the two prongs 28 and 30 is a web or cross bar 31, which is adapted to be received within the slots 32 in the base or butts of the blades, and to hold the same in position to be projected through the slot 9, or to be retained within the barrel 4, depending upon the angular adjustment of the cap 22. The engagement between the rear ends of the blades and the bar 31 provides an interlocking connection which holds the blades from axial turning, and permits the blades to be turned when the end cap is rotated. The end cap and the plug 27 provide means for controlling the movements of the rear ends of the blades, and 130

constitute one of the important contributions to the construction of my aforesaid application.

The pin 25, the transverse portion of the 5 slot 24, and the sleeve 17 are so related as to aline the blades ready for issuance through the slot in the chuck when the end cap is turned to the extreme left, and to turn the blades into a position where they 10 are practically at right angles to the said slot when the cap is turned to the extreme right.

A plurality of holes 29 are provided for the purpose of advancing the plug 27 in the 15 cap, whenever the ends of the blades have been worn and filed down and thereby shortened.

Portions of the outer surfaces of the magazine, and cap, the chuck body, and the 20 chuck cap are milled or otherwise roughened, as shown, to assist in turning these parts by hand.

The selection of the blades is accomplished in a manner similar to that of my former 25 construction, the opening 19 being shaped as shown in Fig. 12, approximating a Maltese cross, being widened in two different directions. This opening corresponds with an opening in a similar part in my former 30 device. Three blades are shown in the drawings. When it is desired to use the middle blade, the chuck 12 and the end cap 22 are brought into the proper position (Fig. 7), by holding the tool at both ends 35 and turning it to the left. The tool is then held in a horizontal position with one of the recesses 33 of the opening 19 in the lowermost position, and the three blades arranged edgewise, one flat against the 40 other, as shown in Fig. 9. This brings the middle blade into alinement with the openings 9 and 15, whereupon by tilting downwardly the tool at the front end, the middle blade will slide out by gravity through the 45 openings 9 and 15.

When one of the outer blades is wanted, the tool is held with one of the recesses 34 lowermost, all three blades assuming the 50 position as shown in Fig. 9^a, whereupon the topmost blade will be in alinement with the openings 9 and 15, after which by tilting the tool downward, as before, the topmost blade is projected through the openings 9 and 15.

Suitable indicia 35 is provided on the 55 barrel, as explained in my former application, to mark which side of the barrel should be held uppermost to correspond to each of the blades. The blades are also correspondingly marked.

The slot 9, notches 15, and the selected 60 blade are brought into alinement merely by taking the chuck cap 12 between the thumb and forefinger of one hand, and the end cap 22 between the thumb and forefinger of the other hand, and rotating the same in

opposite directions, the chuck cap being rotated to the right and the end cap to the left. Upon the issuance of the selected blade, a slight pull on the blade compresses the spring 20 and brings the notches 10 of 70 the blade opposite the contracted extremity 11 of the chuck cap. The chuck cap may then be turned to the left to lock the blade in its projected position as shown in Figs. 1 and 6, the end cap 22 being by the same 75 movement rotated to the right to clamp the remaining blades as shown in Figs. 3 and 10, and prevent the same from rattling.

To retract the blade again into the magazine, it is not necessary to manipulate the 80 blade itself, but by merely giving the chuck cap a quick turn back to the alined position of the notches, (Fig. 7), the blade will snap back into the magazine, the only necessary condition being that the screw driver 85 be held with the same side uppermost as when the blade was projected, and with the body of the tool slightly tipped downwardly and backwardly.

It will be understood, from the foregoing 90 description, that this arrangement of the chuck cap and end cap makes it possible to extend the blade ready for use, or to close it ready for carrying by a single movement; that is, by taking hold of the chuck cap with 95 one hand and of the end cap with the other, one turn to the left unlocks the screw driver ready for use by alining the blades with the slot, and the slot with the notches in the chuck cap. One turn to the right disalines 100 the notches in the chuck cap with the blade-receiving slot 9, and disalines the latter with the blades, thereby positively preventing the issuance of the blades from the magazine. 105

In addition to this locking action, effected by the end cap, it serves the additional and very important purpose of holding the blades remaining in the magazine from rattling. After a blade has been issued, then, by giving the cap a slight turn to the right, the blades in the magazine are turned and wedged against the blade in use, as will be understood from Figs. 3 and 10. This results not only in the prevention of any rattling while using the tool, but serves to set the blade being used still more rigidly, the degree of rigidity obtained by these various means being, in fact, quite remarkable in view of the rapidity and ease with which the 110 tools can be issued and retracted.

The same mechanism which prevents the blades from rattling when one blade is in use is also available when all blades are in the magazine. By placing the end of one 125 finger over the opening in the chuck and partially issuing any one of the blades, and then turning the end cap, as above described, a similar wedging action of the other two blades against the blade thus partially is- 130

sued, is obtained, and all rattling effectively stopped. At the same time, the position of the blade in the slot serves to keep any foreign bodies from entering the interior of the screw driver.

While I have described this invention as applicable to magazine screw drivers, it is obvious that the invention may be used for containing and holding multiple tools of different sizes, and I, therefore, do not wish to be restricted to the use of my invention for screw drivers alone.

The present construction is superior to other tools of this type, in that the size of the tool in relation to the blade is reduced, there are fewer comparatively large, heavy and expensive parts, the construction of the tool is simplified, and its manipulation is rendered easier, less time is consumed in inserting and retracting the blades, and the tools in use can be set more rigidly and can be instantly locked against rattling, this last result being accomplished without the necessity of any additional parts.

25 What is claimed is:—

1. In a magazine tool, a barrel adapted to receive one or more blades, a chuck at one end of the barrel and having a slot extending centrally therethrough, means for rotating a blade within the barrel so as to aline or disaline it with the slot, said blade when so alined being free to issue from the slot, and means for locking it in its projected position.

2. In a magazine tool, a barrel adapted to receive one or more blades, a chuck body at one end of the barrel and having a slot extending centrally therethrough, means for rotating a blade within the barrel so as to aline or disaline it with the slot, a chuck cap having a pair of opposed notches and rotatable to bring said notches into alinement or disalinement with said slot, the slot and notches when so alined being of sufficient width to permit the complete projection of the blade, and means for locking the blade in projected position.

3. In a magazine tool, a barrel adapted to receive one or more blades, a chuck secured to one end of the barrel and having a slot extending centrally therethrough, means for rotating a blade within the barrel so as to aline or disaline it with the slot, a chuck cap having a pair of opposed notches and rotatable to bring said notches into alinement or disalinement with said slot, the slot and notches when so alined being of sufficient width to permit the complete projection of the blade, said blade having notches engageable by the chuck cap when the latter is disaligned to lock the blade in projected position.

4. In a magazine tool, a hollow barrel, a chuck body at one end thereof having a centrally-disposed slot, means whereby the tools may be selectively projected through said slot, a chuck cap having a pair of notches

and having limited rotational movement on the chuck body to bring said notches into alinement or disalinement with said slot, a spring washer between the chuck body and chuck cap to hold the latter in its adjusted position, and means for locking the tool in projected position.

5. In a magazine tool, a barrel adapted to receive a plurality of blades, each blade having opposite notches at its sides, a chuck body at one end of the barrel and having a slot extending centrally therethrough, said barrel being in communication with the slot to discharge a blade into or through the latter and a chuck cap mounted on the chuck body to turn to a limited extent thereon, said chuck cap having a contracted portion to engage the notches in the blades to lock the same.

6. In a magazine tool, a barrel, a plurality of blades within the barrel, means for permitting selective projection of any one of the blades to working position, means for locking the projected blade against retraction and means optionally movable to clamp the remaining blades within the barrel to prevent rattling.

7. In a magazine tool, a barrel, a plurality of blades within the barrel, means for permitting selective projection of any one of the blades to working position, means for clamping the blade in working position, and means operable by the user for holding the remaining blades within the barrel to prevent rattling.

8. In a magazine tool, a barrel, a plurality of blades within the barrel, said blades being free to move within the barrel longitudinally and laterally in either of two transverse directions in response to gravity as the position of the tool may be changed, means within the barrel for restricting the movements of the blades by gravity to cause a selected one of the blades to be projected from the end of the barrel into working position, and means for simultaneously locking the projected blade against retraction and clamping the remaining blades within the barrel to prevent rattling.

9. In a magazine tool, a barrel adapted to receive a plurality of blades, a chuck secured to the front end of the barrel and having a slot extending centrally therethrough, means at the rear end of the barrel having a limited rotational movement, said blades being constrained to rotate with said means into or out of alinement with said slot, one of said blades when so alined being free to issue from the slot depending upon which side of the tool is uppermost, and means for locking the projected blade in position.

10. In a magazine tool, a barrel adapted to receive a plurality of blades, a chuck secured to the front end of the barrel and having a slot extending centrally therethrough,

- a cap at the rear end of the barrel having a limited rotational movement therein, said blades being constrained to rotate with the cap into or out of alinement with the slot, 5 a chuck cap having a pair of opposed notches and rotatable on the chuck to bring said notches into alinement or disalinement with said slot, and means for locking the blade in projected position.
- 10 11. In a magazine tool, a barrel, a plurality of blades within the barrel, means for permitting selective projection of any one of the blades to working position, means for locking the projected blade against retraction, and resilient means put under tension 15 by the blade when projected for automatically withdrawing said blade when the locking means is released.
12. In a magazine tool, a barrel, a plurality of blades within the barrel, said blades being free to move within the barrel longitudinally and laterally in response to gravity as the position of the tool may be changed, means within the barrel for restricting the movements of the blades by gravity to cause a selected one of the blades to drop into position to be issued from the barrel, means for locking the projected blade against retraction, and resilient means put 25 under tension by the blade when projected for automatically withdrawing the blade when the locking means is released.
13. In a magazine tool, a barrel, a chuck at one end thereof, a plurality of blades within the barrel, means for permitting selective projection of one of the blades through the chuck to working position, a chuck cap partially rotatable on the chuck, cooperating means on the chuck cap and 30 blade to lock the projected blade against retraction, and resilient means put under tension by the blade when projected for automatically withdrawing said blade when the chuck cap is released therefrom.
- 40 14. In a magazine tool, a hollow barrel having a chuck body at one end, means whereby the tools may be selectively projected from the chuck by gravity, a chuck cap having limited rotational movement in one direction on the chuck body to lock the tool in projected position, and a cap on the other end of the barrel and rotatable in the opposite direction to clamp the remaining tools against rattling.
- 45 15. In a magazine tool, a hollow barrel having a chuck body at one end, means whereby the tools may be selectively projected from the chuck by gravity, a chuck cap having limited rotational movement in one direction on the chuck body to lock the tool in projected position, and a cap on the other end of the barrel and rotatable in the opposite direction to rotate the blades within the barrel.
- 50 16. In a magazine tool, a barrel adapted to receive a plurality of blades, a chuck secured to one end of the barrel and having a slot extending centrally therethrough, means engageable with the rear ends of the blades for rotating them within the barrel and 70 alining them with the slot, a selected blade when so alined being free to issue from the slot, and means for locking said blade in its outermost position.
17. In a magazine tool, a barrel adapted 75 to receive a plurality of blades, a chuck secured to the front end of the barrel and having a slot extending centrally therethrough, a cap at the rear end of the barrel having a limited rotational movement therein, means 80 carried by the cap and engageable with the rear ends of the blades to rotate them into or out of alinement with the slot, one of said blades when so alined being free to issue from the slot, the selection being determined 85 by gravity, and means for locking the blade in its outermost position.
18. In a magazine tool, a barrel adapted to receive a plurality of blades, a chuck at the front end of the barrel having a slot to 90 allow the passage of a single blade and for clamping the same in projected position, and means at the rear end of the barrel engageable with the rear ends of the blades to rotate them into or out of alinement with 95 said slot.
19. In a magazine tool, a barrel adapted to receive a plurality of blades, a chuck at the front end of the barrel having a slot for the passage and the clamping of a single 100 blade at a time, and means at the rear end of the barrel engageable with the rear ends of the blades for turning said blades and locking them from rattling.
20. In a magazine tool, a barrel adapted 105 to receive a plurality of blades, each blade having a slot in its inner end, means for permitting the selective projection of any one of the blades and means at the rear end of the barrel engageable with the slots of the remaining blades, said means being partially rotatable to a limited extent to move the blades bodily to clamp the same against the inner end of the projected blade and prevent them from rattling.
21. In a magazine tool, a barrel having a chuck fixedly secured at one end thereof, said chuck having a slot for receiving one blade at a time, an end cap at the other end of the barrel having a limited rotational movement, a plurality of blades housed within the barrel, and means for causing said blades to rotate with the cap into or out of the plane of the slot, and means for selecting a blade and causing it to issue through the slot by the action of gravity upon turning the tool as a whole.
22. In a magazine tool, a barrel adapted 120 to receive a plurality of blades, a longitudinally movable sleeve within the barrel,

- means for limiting the longitudinal movement of said sleeve and holding the same from rotative movement, said sleeve having an inturned flange at its forward end which
- 5 defines an opening for the passage of the blades, a chuck body carried by the barrel, a spring within the chuck body engaging the forward end of the sleeve, the flange of said sleeve being engaged by the blade when
- 10 projected, said sleeve being moved outwardly against the tension of the spring by by pulling upon the projected blade, and means for locking the blade in its outermost position.
- 15 23. In a magazine tool, a barrel adapted to receive a plurality of blades, a chuck carried at the front end of the barrel having a slot for the passage of one blade at a time, a longitudinally movable sleeve
- 20 within the barrel, means for limiting the movement of said sleeve, a spring engaging the said sleeve, the latter being engaged by the butt end of the blade when projected, said spring being put under tension when
- 25 the blade is in its projected position, whereby when the chuck is released the blade is automatically retracted within the barrel, and means for locking the blade in its outermost position.
- 30 24. In a magazine tool, a hollow barrel adapted to contain a plurality of blades, an end cap having a diametrical interior web, each of said blades having a slot in its base receiving said web, a chuck having
- 35 a slot through which one blade only may issue at a time, said end cap having a limited rotational movement to bring the blades into the plane of the slot through the chuck and rotatable in the opposite
- 40 direction, after one of the blades is either wholly or partially projected, to clamp the blades against rattling.
25. In a magazine tool, a hollow barrel adapted to contain a plurality of blades, an end cap having a diametrical interior web, each of said blades having a slot in its base receiving said web, a chuck having
- 45 a slot through which one blade only may issue at a time, said end cap having a limited rotational movement to bring the blades into the plane of the slot through the chuck, and means for locking the selected blade when projected.
- 50 26. In a magazine tool, a hollow barrel adapted to contain a plurality of blades, a chuck secured to the barrel and having a slot through which one blade only may issue at a time, means formed on the inside of the barrel whereby the blade to be issued
- 55 may be selected by gravity, depending upon the position in which the tool is held, an end cap having a diametrical interior web, each of said blades having a slot in its base receiving said web, said end cap having a
- 60 limited rotational movement to bring the
- blades into the plane of the slot through the chuck and being rotatable in the opposite direction, after one of the blades is either wholly or partly projected, to clamp the blades against rattling.
- 70 27. In a magazine tool, a hollow barrel adapted to contain a plurality of blades, a chuck secured to one end of the barrel and having a slot through which one blade only may issue at a time, an end cap having a portion for insertion into the other end of the barrel, said portion being provided with a T-shaped slot, a pin secured in the barrel and engageable in the T-shaped slot to permit insertion of the cap and limited rotation thereof, means connecting the blades with the cap for rotation therewith but permitting longitudinal movement of the blades independently of the cap, the blades being brought into the plane of the slot of the chuck by rotation of the cap in one direction, the cap being rotatable in the opposite direction, after one of the blades is either wholly or partly projected, to clamp the blades against rattling.
- 75 28. In a magazine tool, a hollow barrel adapted to contain a plurality of blades, a chuck at one end of the barrel, an end cap removably secured in the other end of the barrel, a plug removably secured within the cap and adjustable longitudinally thereof, said plug having two arms connected by a transverse web, each of said blades having a longitudinal central slot in its end which receives said web, the cap and plug having a limited rotational movement to move the blades axially into the plane of the chuck slot to permit one of them to issue or into a different plane to prevent issuance.
- 80 29. In a magazine tool, a hollow barrel adapted to contain a plurality of blades, a chuck at one end of the barrel having a slot for permitting the issuance of a selected one of the blades, an end cap removably secured in the other end of the barrel, a plug removably secured within the cap, said plug having two arms connected by a transverse web and adjustable longitudinally of the cap, each of said blades having a longitudinal central slot in its end which receives said web, the cap and plug being rotatable in one direction to bring the blades into position where one of them may issue through the chuck slot, and rotatable in the opposite direction to clamp the remaining blades against rattling, and a chuck cap rotatable on the chuck in a direction opposite to the last mentioned rotation of the plug to lock the blade in projected position.
- 85 105 110 115 120 125
- In testimony, that I claim the foregoing as my own, I have hereunto affixed my signature.
